Primary Examiner — Amber R Stiles*Assistant Examiner* — Christen Pilar Brown-Lorrig(74) Attorney, Agent, or Firm — Wilmer Cutler Pickering Hale and Dorr LLP(57) CLAIM

The ornamental design for a shoe as shown and described.

DESCRIPTION

FIG. 1 is a perspective view of a shoe showing my new design;

FIG. 2 is a left side view of the shoe of FIG. 1;

FIG. 3 is a right side view of the shoe of FIG. 1;

FIG. 4 is a front view of the shoe of FIG. 1;

FIG. 5 is a back view of the shoe of FIG. 1;

FIG. 6 is a top view of the shoe of FIG. 1; and,

FIG. 7 is a bottom view of the shoe of FIG. 1.

The broken lines in the Figures show portions of the shoe which form no part of the claimed design, but are shown for environment and background.

1 Claim, 7 Drawing Sheets(56)
